DESIGN FOR AN AQUARIUM TABLE

Judy Thomas, Los Angeles, Calif.

Application July 26, 1946, Serial No. 131,951

Term of patent 3½ years

(Cl. D33—14)

To all whom it may concern:

Be it known that I, Judy Thomas, a citizen of the United States, residing at Los Angeles, in the county of Los Angeles and State of California, have invented a new, original, and ornamental Design for an Aquarium Table, of which the following is a specification, reference being had to the accompanying drawing, forming part thereof.

Figure 1 is a view in perspective as viewed from an end of an aquarium table embodying my new design; and

I claim:

The ornamental design for an aquarium table, substantially as shown.

JUDY THOMAS.
